UNITED STATES PATENT OFFICE

FRANS O. ALBERTSON, OF SIOUX CITY, IOWA, ASSIGNEE TO ALBERTSON & COMPANY, INC., OF SIOUX CITY, IOWA, A CORPORATION OF IOWA

REAMER CUTTING MACHINE

Application filed December 16, 1929. Serial No. 414,392.

The present invention relates to reamer cutting machines, and is particularly concerned with the provision of an improved reamer cutting machine which is peculiarly adapted for the manufacture of improved valve seat finishing reamers having new and desirable operating characteristics.

The reamer adapted to be manufactured by the present machine, and the methods of making reamers and finishing valve seats, are the subject of another application filed by Frans O. Albertson on November 18, 1929, Serial No. 407,877, for valve seat finishing tools and methods of making the same and while some of the desirable operating characteristics in a valve reamer might be attained by the use of other machines for making the reamers, the present machine is an example of the preferred embodiment for constructing reamers of the type shown in my prior application.

In the finishing or reseating of the valves of internal combustion engines, the reamers or other tools of the prior art have not been capable of forming a perfectly finished valve seat, and it has always been necessary to use a lapping or grinding operation in order to attain the degree of perfection which is desirable for modern internal combustion engines.

This grinding or lapping operation is usually performed with the valve in place, by putting a small amount of grinding compound on the seat or valve and by oscillating the valve upon its axis with the valve engaging the seat, and the grinding of the valve on the seat is relied upon to secure a perfect fit between the valve and the seat in the devices of the prior art.

The reason for such lapping or grinding operation was that it was practically impossible for the prior reamers to finish a valve seat with a uniformly perfect seating surface and a close examination and test of the valve seats made by the tools of the prior art shows that there are numerous waves in the surface of the valve seat, consisting of minute hills and valleys, generally extending radially with respect to the axis of the valve and seat.

One of the most important factors contrib-

uting to this lack of perfection of the valve seats made by the prior tools was the tendency of the reamer to chatter, instead of cutting evenly and smoothly, and those skilled in the art have sought for many years to avoid the chattering of the reamer, generally by varying the number of teeth used and by using an odd number of teeth.

None of the devices of the prior art have been able entirely to eliminate the chattering and resultant high and low spots produced in the valve seat, and consequently the finishing of valve seats with the tools of the prior art always consisted of at least a two-step method, the last step being the lapping in of the valve with the valve grinding compound and a machine for oscillating the valve.

One of the objects of the present invention is the provision of an improved reamer cutting machine which is adapted to produce an improved valve reamer capable of finishing valve seats by an improved one-step method, by means of which the customary grinding or lapping operation may be eliminated.

Another object of the invention is the provision of an improved machine capable of producing improved valve seat reamers or valve reconstruction tools, which have the inherent capability of producing a substantially perfect valve seat surface.

Another object is the provision of an improved machine adapted to manufacture reamers having improved operating characteristics from which the undesirable factor of chattering or uneven cutting, present in the reamers of the prior art, have been eliminated.

Another object is the provision of an improved machine which is capable of the economical and expeditious cutting of teeth for valve seat reamers or the like, having a plurality of teeth which are located at different spacing from each other, each at a slightly different angle with respect to the angularity of the surface relative to the axis of the reamer, and each having a different angularity with respect to the elements of the conical valve seat surface.

Other objects and advantages of the inven-

tion will be apparent from the following description and from the accompanying drawings, in which similar characters of reference indicate similar parts throughout the several views.

6 Referring to the drawings, of which there are six sheets;

Fig. 1 is a side elevational view of a reamer cutting machine constructed according to the 10 present invention, with a portion of the base cut away;

Fig. 2 is a front elevational view of the same machine, with certain parts in section on the plane of the line 2—2 of Fig. 1 to illustrate the mechanism;

15 Fig. 3 is a plan view of the guide for the table, partially broken away to show the mechanism for feeding the table;

Fig. 4 is a sectional view on the plane of the line 4—4 of Fig. 6 through the eccentric spindle, for supporting the reamer blank;

Fig. 5 is a plan view of the dividing head;

Fig. 6 is a sectional view taken on the plane of the line 6—6 of Fig. 5, looking in the direction of the arrows;

Fig. 7 is an enlarged bottom plan view of a 45° reamer made by the present machine;

Fig. 8 is a sectional view taken on the plane of line 8—8 of Fig. 7;

30 Fig. 9 is a diagrammatic, elevational view showing the relation between the milling cutter and reamer blank during the cutting operation;

Fig. 10 is a plan view in partial section, of the automatic table elevating mechanism; and

35 Fig. 11 is a vertical sectional view taken on the plane of the line 11—11 of Fig. 2, through the table supporting and adjusting mechanism.

40 As an understanding of the results sought to be accomplished, and the characteristics of the reamer manufactured by the present machine, is essential to an understanding of the machine, I shall first briefly describe the structure and characteristics of the improved reamers made by the present machine. These features are more fully described in my above mentioned prior application.

Since the improved features and characteristics of the teeth are difficult to distinguish with the naked eye, the views of Figs. 7 and 8 have been drawn on a scale three times the actual size of one of the commercial reamers.

50 The reamers are preferably constructed of substantially cylindrical bodies 10 of the best tool steel and provided with a substantially flat upper surface 11 for engagement with feeding devices and with a slightly tapered bore 12 having its largest end located at the 55 top 11 of the reamer, so that the reamer 10 may be secured upon a tool holder by the frictional fit of a complementary tapered portion in the tapered bore 12.

60 The body 10 of the reamer is cut away at 65 regular intervals around the lower and outer

edge of the reamer, with a plurality of cuts, preferably of triangular section, forming substantially flat walls 15 and 16 on each side of the cut, forming the teeth 17 provided with cutting edges 18. The cuts which form the walls 15 and 16 are made diagonally with respect to a certain axis on the reamer, so that the teeth 17 thus formed, extend substantially along the angle of the reamer desired.

70 Thus, for a 45° reamer, the general direction of the feed of the cutting tool is at 45° to the axis of rotation of the reamer which is being cut, but reamers may be made of any angularity, the ordinary commercial sizes of reamers being 15°, 30°, 45°, 50°, 60° and 75°, 75 and it will be understood that any desirable size of reamer may be constructed.

80 It should be understood that the exact shape of the cuts produced by the cutting tool depend upon the type of tool employed, and the provision of substantially flat sides on the teeth 17 is incidental to the cutting of reamers with milling tools.

85 One of the most important features of the present reamer is the exact direction in which cutting edges 18 extend with respect to the true axis of the reamer. The true axis is indicated by the numeral 19 and an eccentric axis upon the horizontal base line 20 is indicated by the numeral 21.

90 It has already been pointed out that the cutting edges of the reamers of the prior art produce minute irregularities such as hills and dales, extending radially of the surface of the valve seat, and it will be evident that the radial teeth of the reamers of the prior art would naturally fall into such valleys or dales between successive high points, thereby accentuating the undesirable result when it has once begun.

95 The cutting edges of the reamers constructed according to the present invention, do not all extend radially at the same angle to the axis of the reamer as in the devices of the prior art, but the various teeth, or certain of them, extend at substantially different angles to each other and to the axis of the reamer.

100 The effect of this change in the direction of the cutting edges can best be understood by comparing the action of two radial cutting edges such as are provided in the prior reamers, with two of the cutting edges of the present tools.

105 Assuming that one of the prior reamers had radial teeth and the first tooth chattered slightly and produced some radially extending valleys and hills on the seat, the next radial tooth would be exactly in line with the direction of these valleys and the undesirable chattering effect would be accentuated with further undesirable results. Assuming that the present valve tool was employed upon a seat which had such a radially extending irregularity, if one of the teeth happened to fit this irregularity in alignment, the next 110

tooth would be at a different angle, so that it would straddle the valley and also produce some shearing effect on the seat during the cutting operation. Thus, each of the cutting edges of the present reamer is preferably disposed at a slightly different angle, but the amount of divergence between a radial line and the cutting edges is so minute that it cannot be distinguished by the naked eye alone.

In the reamer manufactured by the present machine, which represents a form most conveniently and economically manufactured, the cutting edge 22 extends radially with respect to the true axis 19 of the reamer, but at substantially 45° to said axis in a 45° reamer. Since the same principles may be applied to reamers of any angle, it is only necessary to describe the 45° reamer, and the term "radially" is used in the generic sense to include all of the lines in any radial plane, that is, a plane which includes the axis of the reamer. All of the other cutting edges 23 to 35, inclusive, extend along lines drawn to the point 21 which is spaced slightly from the true center 19.

It will thus be observed that all of the cutting edges extend substantially along lines which are radial with respect to the eccentric point or axis 21, and consequently the angle between the cutting edges and a true radial or plane, increases by steps from the edge 23 to the edge 29, and decreases by steps from the edge 30 to the edge 36, the divergence between the cutting edge 22 and the radial line being theoretically equal to zero.

Each of the teeth 17 is provided with a slightly flat or concavely curved surface 37, which is formed by the sharpening operation, and the juncture of the surfaces 27 and 16 on the various teeth, forms the cutting edges 22 to 36, inclusive. The particular form of teeth illustrated and described, is the result of the method of manufacture which will now be described in detail.

The exact location and direction of the teeth is difficult to determine on account of the minute measurements required and the complexity of the geometrical problems involved in specifying the exact direction, but the foregoing description has been provided in order to give one accepted theory of the operation of the present tool in forming a perfectly finished valve seat.

The angularity of the teeth varies, not only with respect to radial lines drawn from the axis of the reamer, but certain of the teeth vary by a very slight degree from the 45° angle desired on the valve seat, as, for instance, in Fig. 8 the tooth 33 happens to be at an angle of $44^{\circ} 58'$ to the horizontal, while the tooth 26 is at an angle of $45^{\circ} 2'$ to the horizontal as indicated.

This result is thought to be due to the clearance which is provided for the cutting edge during the grinding or sharpening oper-

ation, and another theory of operation of the present cutting edges is that the reamer is provided with one edge or tooth extending truly at an angle of 45° , whereas the other teeth not only diverge laterally from the radial lines, but also diverge upward or downward from the true 45° , tending to cut deeper at one end and shallower at the other end, but the composite result of the entire set of teeth is known to be a practically perfect 45° valve seat.

Referring to Figs. 1 and 2, the reamer cutting machine selected to illustrate the invention, preferably includes a supporting base 50 which is provided with an upwardly extending column 51 having a cutter shaft 41 rotatably mounted therein and provided with a plurality of pulleys 52 of different sizes. The head of the column 51 preferably supports a forwardly extending bar 53 having a depending bearing member 54 for the cutter shaft 41, and the shaft 41 is adapted to support any one of a plurality of different milling cutters 40.

Referring to Fig. 9, the preferred milling cutter is provided with a plurality of cutting edges 55 and 56 which may extend in such manner that the milling cutter 40 is adapted to make a substantially triangular cut forming the teeth 17 in the reamer 10, the teeth having relatively flat side walls 15 and 16.

The column 51 of the machine is preferably provided with a vertically extending guide 57 of substantially trapezoidal cross-section, as shown in Fig. 3, having inclined side walls 58 so that the guide 57 tapers in width from its outer corners, inward to the body of the column 51.

The machine is also provided with a supporting member 59, usually termed a "knee", which is adapted to provide a support for a plurality of sliding carriages 60, 61, a dividing head 62 and other mechanism necessary for the support of the reamer body 10, from which the finished reamer is made.

The knee 59 is therefore provided with laterally projecting guide members 63 adapted to embrace the tapered guide member 57 on column 51, and slidably support the knee 59 on the column 51. In order to provide a manually adjustable and also automatically adjustable support for the sliding knee 59, the knee is preferably formed with a bearing 64 for rotatably receiving a vertical screw shaft 65, and the lower end of screw shaft 65 is rotatably supported by a slider 66. The slider 66 is provided with a threaded bore 67 for receiving the lower threaded portion 68 of the screw shaft 65, and the knee 59 is provided with an aperture 69 for receiving the slider 66, and with a collar 70 having a bore 71 for receiving the cylindrical portion 72 of the slider 66.

The slider 66 and collar 70 are provided with registering slots 73, 74, respectively, for

receiving a key 75 adapted to prevent rotation of the collar 70, and the downwardly inclined body 76 of collar 70 is fixedly secured to the knee 59 or held in position by the weight of the knee 59 and its associated mechanism.

The lower end of the collar 56 is provided with a laterally projecting portion 77 forming a thrust bearing surface 78 for supporting the collar 70, knee 59 and associated mechanism, and the laterally projecting portion 77 is provided with a vertically extending slot 79 and a pair of registering bores 80 for receiving a stub shaft 81 which rotatably supports a roller 82.

The upper end of shaft 65 is provided with a bevel gear 83 adapted to mesh with a bevel gear 84 carried by a horizontally extending shaft 85, rotatably mounted in bearings 86 in the knee 59 and provided with a crank 87.

The base 50 of the milling machine is preferably provided with a forward extension 88 adapted to provide a support for a platform 89 which carries a vertically extending shaft 90 for rotatably supporting an elevation plate 91. The elevation plate 91 may consist of a circular member provided with a plurality of teeth 92 having substantially radial shoulders 93 on one side, and inclined camming surfaces 94 on the other side, and the plate 91 is provided with an annular camming surface 95, the elevation of which is varied to vary the elevation of the knee 59, and all of the associated mechanisms supported thereby.

In manufacturing reamers of the type described, it is preferable that the depth of cut be changed with respect to each successive tooth, thereby varying not only the space between the teeth, but the relative angularity of the respective teeth, and in order to accomplish this result, the plate 91 is provided with the camming surface 95 which has a different elevation for each successive tooth to be cut. Thus, where it is desired to make a fifteen tooth reamer, the machine is provided with a plate 91 having fifteen surfaces 96 of different elevation, forming an annular camming surface 95.

Although the annular camming surface 95 is shown with radial lines 97 to indicate the divisions between the successive camming surfaces 96, it should be understood that the transition in elevation between successive surfaces 96 may be gradual, so that the rotation of the plate 91 is adapted to cam upward the roller 82, knee 59 and the carriages supported thereby.

It should also be understood that the present construction is not limited to the type of reamer in which each and every one of the teeth differs in depth from each and every other tooth, but that certain of the cuts which are at some distance from other cuts, may be substantially similar in depth if desired, and

the reamer illustrated is exemplary of one which will give the best results. However, the variation between the spacing and angularity of the teeth may be changed infinitely by merely changing the physical constants of the camming surface 95.

The knee 59 is preferably provided with a substantially horizontal, forwardly extending guide 98 of substantially trapezoidal cross-section, having lateral walls 99 and 100 which incline outward and upward, so that the width of the guide 98 tapers toward the body of the knee 59. The knee 59 supports a carriage 60 which is provided with a slot 102 of a cross-section complementary to the guide 98, so that the carriage 101 is adapted to be slidably supported on the knee 59. The carriage 60 is provided with a depending lug 101 having a threaded bore 103 for receiving the threaded end 104 of a shaft 105, which is rotatably, but non-reciprocably, supported in the knee 59, and provided with a non-circular end 106. The carriage 60 may thus be slid forward or backward by the application of a crank or tool to the squared end 106 of shaft 105, and it will be evident that rotation of the shaft 105 will cause the table 60 to advance or recede.

The table 60 is also provided with a groove 107 adapted to receive a guide member 108 of similar form to those already described, carried by the carriage or table 61, and the guide member 108 is preferably located at right angles to the guide 98 so that the table 61 may be moved transversely to the axis of the cutter shaft 41.

In order to provide means for moving the table 61 and feeding the reamer into the cutter 40, the carriage 60 is preferably formed with a diagonally extending bearing 109, which rotatably, but non-reciprocably, supports a shaft 110, and the shaft 110 is provided with radially extending handles 111 and with a screw thread 112 adapted to engage a rack 113 carried by the table 61. A rotation of the shaft 110 by means of the handles 111, causes the table 61 to traverse the field of the cutter 40, and the reamer may thus be fed against the cutter 40 or withdrawn as desired, by actuating the handles 111.

The table 61 is preferably provided with a plurality of transversely extending slots 114 of substantially T-shaped cross-section, for slidably receiving the heads of a plurality of bolts 115 which secure the base 116 of the dividing head 62 to the table 61, and the dividing head 62 may thus be secured in any of a plurality of convenient positions.

Referring to Figs. 2, 5 and 6, the dividing head 62 preferably includes a base 116 which rotatably supports a substantially cylindrical body 117 for rotation about a horizontal axis, which is parallel to the axis of the shaft 41. The cylindrical body 117 is pro-

vided with a scale 118 which indicates the variation of a spindle 119 from its horizontal position, and the scale 118 cooperates with a pointer 120 carried by base 116.

5 A thumb nut 121 is provided on the body 117 for securing the body 117 in any of a plurality of positions, as, for example, the position shown in Fig. 2. The body 117 is provided with a gear chamber 122, and with 10 a pair of aligned bores 123 for receiving a sleeve 124 carrying a worm gear 125. The sleeve 124 has a tapered bore 126 at its right-hand end in Fig. 6, for receiving a tapered sleeve 127 which is provided with screw 15 threads 128 adapted to cooperate with complementary threads on the sleeve 129.

The sleeve 129 has a head 130 at its outer end provided with sockets 131 for receiving a wrench and an anti-friction bearing comprising a pair of races 132, and a plurality of balls 133 may be interposed between the head 130 and a bushing 134 carried by sleeve 129.

20 The tapered sleeve 127 may be provided 25 with a split end adjacent the bore 135 for receiving the spindle 38, and when the spindle 38 is located in bore 135 and the sleeve 127 is drawn into the tapered bore 126 by rotating the sleeve head 130, the spindle 38 30 is firmly gripped by the sleeve 127, forming a substantially firm connection between the spindle 38 and the sleeve 124.

The spindle 38 is preferably provided with 35 a thrust bearing 136 and with a tapered reamer supporting portion 39, the axis of which is located eccentrically with respect to the axis of the spindle 38 as shown in Fig. 4.

The cylindrical body 117 is also provided 40 with bearings for supporting a forwardly extending screw shaft 137, which is adapted to engage and actuate the screw gear 125 and the shaft 137 is provided with a crank 138 having a handle 139 provided with a pin 140 45 and adapted to be slid axially to withdraw the pin 140 from a plate 141.

The plate 141 is fixedly supported upon the cylindrical body 117 and provided with the minimum amount of holes necessary to 50 secure the handle 128 in a plurality of different positions necessary to be used in advancing the reamer 10 step by step from the position of one tooth to the position of the next succeeding tooth. In the present embodiment, the gear ratio is such that one and two-thirds turns of the handle 138 is sufficient to advance the spindle 38 and reamer 10 to the position for cutting the next tooth, and consequently the plate 141 is provided with 55

60 three apertures 142, thereby eliminating the many apertures which are usually provided in the securing plates of dividing heads and adapting the present machine to the manufacture of the present reamers.

65 In order to automatically move the table

61, dividing head 62 and reamer 10 to the proper elevation for the cutting of the successive teeth, the present machine is preferably provided with pneumatic devices for automatically moving the elevation plate 91 70 step by step into the successive positions necessary to give the reamer 10 the desired predetermined elevation.

Referring to Fig. 10, the platform 89 also 75 preferably supports a cylinder 143 which is provided with a cylinder head 144 for slidably supporting one end of a piston rod 145. The cylinder head 144 is provided with a packing 146 which may be compressed by means of the screw sleeve 147 and the piston rod 145 fixedly supports a piston 148, which 80 may be provided with piston rings 149.

The opposite end of the rod 145 is slidably supported in a bore 150 which is formed in an upwardly extending lug 151 carried by the platform 89, and the rod 145 fixedly supports a laterally projecting lug 152 which is secured in adjusted position by a set screw 153. The lug 152 pivotally supports a pawl 154, which is urged into engagement with the 90 teeth 92 by a spring 155, the spring being coiled about a pin 156 carried by a pair of upwardly projecting ears 157 on the lug 152.

In order to maintain the pawl 154 in proper 95 position for engagement with the teeth 92, and to prevent rotation of the piston rod 145, the piston rod 145 may be provided with a cross-head 159a, which is slidably supported by a pair of guides 160 carried by platform 89. The guides support an adjustable stop 100 150 for determining the travel of the pawl for any number of teeth.

The ends of the cylinder 143 are provided 105 with conduits 161, 162 leading from the interior of the cylinder 143 to a valve casing 163, and the conduits 161, 162 preferably include flexible hose so that the valve casing 163 may be carried by the table 60, the hose permitting relative movement between these 110 parts.

The valve casing 163 is provided with a pair of discharge openings or conduits 164, 165, and with a centrally located supply conduit 166, which is connected to a source of fluid pressure, such as the compressed air tank (not shown), and the conduits 161, 162 communicate with the valve casing 163 at points intermediate the supply conduit and discharge conduits, respectively.

The valve casing 163 is preferably provided 120 with a piston valve 167 which is formed with annular grooves 168, 169, which are proportioned in such manner that when the piston 167 is in the position of Fig. 2, at the bottom of its travel the conduit 166 is in communication through the groove 168 with the conduit 161, and when the piston valve 167 is at the upper limit of its travel, the conduit 166 125 is in communication with conduit 162 through the groove 169.

The discharge conduits 164, 165 are located to register with the grooves 168, 169, respectively, when the piston 167 is at the upper limit or the lower limit of its travel, respectively, and it will thus be observed that when the parts are in the position of Fig. 2, the cylinder 143 is adapted to receive a supply of air under pressure through the conduits 166, groove 168, conduit 161, while the conduit 162, 10 which communicates with the other end of the cylinder 143, is in communication with the atmosphere through the grooves 169 and associate conduit 165.

The piston valve 167 thus controls the 15 supply of fluid pressure to the cylinder 143, so that the piston 148 may be reciprocated step by step to rotate the plate 91, depending upon the control of the piston valve 167.

The piston valve 167 is provided with a 20 piston rod 170 having a link 171 which connects to a lever 172, and the lever 172 is pivotally mounted on the carriage 60 by means of a bolt 173 carried by a sheet metal bracket 174. The left end of the lever 172 25 carries a roller 175 which is adapted to be engaged by the upwardly projecting arm 176, and the downwardly projecting cam 177 carried by the table 61. The cam 177 is adapted to engage roller 175, when the table 30 61 moves to the right in Fig. 2, moving the lever 172 counter-clockwise and drawing the piston valve to its upper position from the position of Fig. 2, while the cam 176 is adapted to return the piston 167 to the position of Fig. 2 on the return movement of the 35 table 61.

The operation of the automatic step by step mechanism for producing a predetermined elevation of the reamer blank, and consequently a predetermined depth of cut, spacing and angularity for each tooth, is as follows.

Referring to Fig. 10, the pneumatic step by step mechanism is shown in the position 40 which it occupies just after the elevation plate 91 has been moved to a new position, and before the operation of cutting another tooth on the reamer.

Referring to Fig. 2, the rear end of the 50 cylinder 143 is in communication with the source of fluid pressure 166 through the conduit 161 and groove 168 of valve 167.

When the table 61 is moved to the left by 55 rotating the handles 111 of the shaft 110 in a clockwise direction, (Fig. 2), the body of the reamer 10 is fed against the milling cutter 40, thereby cutting a tooth in the reamer 10. The cam 177 is located on the table 61 in such position relative to the roller 175 that 60 the cam 177 does not engage roller 175 until the reamer has passed the milling cutter, at which time the cam 177 engages roller 175, moving roller 175 downward, rotating lever 172 counterclockwise and moving valve 167 65 to its upper position.

This closes exhaust conduit 165 and shuts off the source of fluid pressure to conduit 161, but places conduit 161 in communication with exhaust conduit 164. The cylinder 143 is then in communication with the source of fluid pressure 166 through conduit 162, and groove 169, and the action of the fluid pressure on the forward end of piston 148 moves the piston from the position of Fig. 10 to the upper end of cylinder 143. 70

The pawl 154 is thus moved back beyond the next tooth 92 on the elevation plate 91 in position to produce further movement of the elevation plate 91 as soon as fluid pressure is supplied to the rear end of the piston 148. 75

The hand levers 121 are then rotated in a counter-clockwise direction, and the table 61 is moved to the left by screw 112 and rack 113, during which movement the reamer 10 passes the cutter 40 through the cut previously formed. As soon as the reamer 10 has cleared the cutter 40 on its return movement, the lower cam 176 then comes into engagement with the roller 175, moving roller 175 upward, and rotating lever 172 clockwise to move the piston 167 from its upper position to the position of Fig. 2. 80

Fluid pressure is then admitted to the upper or rear end of cylinder 143 through 85 conduit 161, groove 168 and conduit 166, as illustrated in Fig. 2, and the piston 148 is immediately moved to the position of Fig. 10. During this movement, the pawl 154 engages the shoulder 93 upon the adjacent tooth 92 90 and advances the elevation plate 91 one step, and the roller 82 on the slider 66 which supports the knee 59, carriages 60, 61 and reamer 10 is raised or lowered by the elevation plate 91, so that the elevation of the reamer for 100 any tooth may be predetermined by the elevation of the camming surfaces 95 on the plate 91, and the elevation plate 91 determines the depth of cut at any tooth in the reamer 10. 105

The elevation plate 91 is preferably provided with a number of camming surfaces 95 equal to the number of teeth desired in the reamer 10, and the cam plate 91 is also provided with an equal number of teeth 92 110 so that when one reamer has been made, the cam plate 91 has progressed step by step through its entire series of positions until it is again in position to begin the cutting of a new reamer. The camming surfaces 95 on the plate 91 may take any predetermined form, but they are preferably provided with relatively flat surfaces at each of the points of rest of the roller 82, so that the elevation of the roller 82 may be accurately predetermined and not affected by slight variations in the rotative position of the plate 91. 120

It will thus be observed that the pneumatic mechanism just described, is capable of automatically determining the depth of 125 130

cut of the milling cutter 40 in the reamer 10, and the reamer may be moved backward through the milling cutter to the position for a new cut before the elevation of the reamer is changed.

5 It should be noted that it is desirable that the reamer be moved back to its initial position before the elevation of the reamer be changed, for the reason that the next cut may not be as deep as the cut just completed, in 10 which case it would be impossible to back the reamer through the last cut after the new adjustment in elevation.

15 The operation of the reamer cutting machine in the manufacture of the reamers previously described, is as follows.

20 Referring to Figs. 1 and 11, the initial position of the table 61 is determined by the depth of the first tooth cut in the reamer 10, and the table 61 may be adjusted in its elevation without affecting the operation of the cam plate 91 by merely rotating the crank 87. When the crank 87 is rotated in a clockwise direction, the shaft 85 is rotated in a similar direction, rotating the shaft 65 in a similar direction by means of the bevel gears 83, 84, and the screw threads 68 on shaft 65 react against the threads in the slider 66, to raise the shaft 65 and with it the knee 59, and all of its associated mechanism. A 25 counter-clockwise rotation of the crank 87 will reduce the elevation of the reamer supporting mechanism by lowering the knee 59.

30 The reamer body 10 is first located upon the eccentric portion 39 of the spindle 38, and if the reamer to be manufactured is a 45° reamer, the cylindrical body of the dividing head 62 is rotated until the reamer spindle 38 points upward at an angle of 45° to 35 the horizontal, as indicated by the scale 118 with respect to pointer 120. The spindle 38 may be fixed in different angular position by means of the thumb screw 121, and the pin 140 of crank 139 is located in one of the 40 apertures 142 to prevent rotation of the spindle 38.

45 It is essential that the cutting of the reamer should begin with the eccentric part 39 of spindle 38 in the proper position with respect to the position of the cam plate 91, because the cam plate varies the elevation of the reamer, and the elevation of the camming surfaces on the plate 91 are predetermined by taking into consideration the various elevations of the reamer due to the eccentricity of the arbor 39. However, the starting position of both the plate 91 and spindle 38 may be determined by appropriate marks on each of these elements of the mechanism, and if the operation is once begun with the parts in the proper relative position, their relative positions will remain correct.

50 Assuming that the first cut is made with the eccentric arbor 39 in its uppermost position, the first cut made will be the cut below

the edge 22 in Fig. 7, and this cut may be accomplished by advancing the reamer body 10 through the milling cutter by means of the hand lever 111, and withdrawing the reamer past the milling cutter in the manner previously described.

55 As soon as the reamer is withdrawn from the cutter, the automatic elevation mechanism is moved one step forward and the elevation plate 91 takes the proper position to raise the reamer or lower it, as the case may be, into a predetermined position for the next cut, the exact position being determined by the elevation of the next camming surface 96 on plate 91. The reamer 10 is then rotated one step into the position for the next cut, and in forming a fifteen-tooth reamer with the present dividing head, the crank 138 is given one and two-thirds turns and the pin 140 permitted to secure the crank in the upper left aperture 142. During this rotation of the crank 138, the spindle 38 has been rotated one-fifteenth of a revolution, but since the reamer 10 is supported upon an eccentric arbor 39, the reamer 10 has been both rotated and revolved in an orbit, the radius of which orbit is equal to the amount of eccentricity.

60 As a result, the next tooth is formed along a line which is radial with respect to the true axis of the spindle 38, which axis is eccentric with respect to the center of the reamer 10.

65 Referring to Fig. 7, it will be observed that the teeth of the reamer extend along lines drawn to the center 21, and if the reamer body 10 is initially provided with a frusto-conical surface 180, the resulting reamer will be provided with relatively flat frusto-conical surfaces adjacent each of the cutting edges 22 to 26.

70 Since the cut which is made in the reamer body is substantially triangular in cross-section, a deeper cut spaces the teeth at greater distance from each other, and a more shallow cut makes teeth which are closer together.

75 An infinite number of different arrangements of the spacing of the teeth may be made, and the spacing illustrated in Fig. 7 is to be regarded as exemplary of but one form of the reamer. The result of this cutting operation is a reamer which has teeth 17 with edges extending along lines converging in the eccentric axis 21, so that all of the edges on the teeth are of substantially different angularity.

80 In order to provide the reamer with a better and more accurate cutting edge, the reamer is thereafter placed upon an ordinary tapered spindle and rotated upon its true axis with respect to a grinding wheel, which is adapted to grind a substantially frusto-conical surface. The grinding wheel preferably turns against the teeth and preferably has its axis located slightly below the axis of the reamer shaft, in order to provide some clearance behind the cutting edge, as described in 85

detail in my prior application, and as a result, it is found that the teeth 22—36 each have a different angularity with respect to each other on a 45° reamer.

5 Since the reamers are ground with a grinding device which would ordinarily produce a frusto-conical surface if other portions of the reamer had not been cut away, the flat surfaces 37 adjacent the cutting edges are 10 substantially portions of a frusto-conical surface, but not exactly so, on account of the slight amount of clearance which is generally desirable. The cutting edges 25 may then be described as substantially lines extending along an imaginary frusto-conical surface, and these are lines which are produced by a cut through a frusto-conical surface so that the cutting edges of the teeth approximate lines geometrically known as conic 15 sections. Such lines are slightly curved, the curvature depending upon the plane through which the conic section is made, and each one of the teeth represents a conic section taken at a slightly different angle.

20 25 The method of use of the reamers which are manufactured by the present machine, is described in detail in my prior application, and this method of valve seat finishing differs from the prior art in the elimination of the step of lapping or grinding the valve and the use of a plurality of cutting edges disposed at different angles enables the production of a perfectly finished valve seat by a one-step method. Manufacturers of motor cars who have always found it necessary 30 in the prior art to grind in their valves are now enabled to produce a perfect finish upon the valve seats, merely by the use of a reamer, thereby greatly decreasing the amount of 35 labor involved and the cost of finishing the valve seats.

40 It will thus be observed that I have invented an improved reamer manufacturing machine, which is capable of producing a reamer having greatly improved operating characteristics. The present machine is 45 particularly adapted to manufacture these reamers economically and expeditiously with a high degree of quality and but very little 50 variation in the dimensions and location of the respective teeth. It should be noted that since the present reamer is intended to actually produce the finished valve seat surface, the teeth should be located with a high degree 55 of accuracy such as can be attained by the use of the present machine.

55 While I have illustrated a preferred embodiment of my invention, many modifications may be made without departing from the spirit of the invention, and I do not wish to be limited to the precise details of construction set forth, but desire to avail myself of all changes within the scope of the appended claims.

65 Having thus described my invention, what

I claim is new and desire to secure by Letters Patent of the United States, is:

1. In a reamer cutting machine, the combination of a supporting base with a cutter carried thereby, means for supporting a reamer body including an eccentric shaft, means for rotating said shaft, step by step, means for feeding said reamer body against said cutter, and means for changing the elevation of said body between successive cuts, to vary the depth, and spacing of teeth formed in said reamer body. 70 75

2. In a reamer cutting machine, the combination of a supporting base with a cutter carried thereby, means for supporting a reamer body including an eccentric shaft, means for rotating said shaft, step by step, means for feeding said reamer body against said cutter, and means for changing the elevation of said body between successive cuts, 80 85 to vary the angularity of teeth formed in said reamer body,

3. In a reamer cutting machine, the combination of a supporting base with a column, a cutter carried by said column, a table movably mounted on said column, a dividing head carried by said table, an eccentric shaft carried by said dividing head for rotatably supporting a reamer blank, means for feeding said blank against said cutter, means for rotating said blank step by step, and means for raising said table to a predetermined elevation for each cut to vary the angularity and depth of teeth formed on said reamer, said means comprising a rotating plate having camming surfaces of different elevation. 90 95 100

4. In a reamer cutting machine, the combination of a supporting base with a column, a cutter carrier by said column, a table movably mounted on said column, a dividing head carried by said table, an eccentric shaft carried by said dividing head for rotatably supporting a reamer blank, means for feeding said blank against said cutter, means for rotating said blank step by step, means for raising said table to a predetermined elevation for each cut to vary the angularity and depth of teeth formed on said reamer, said means comprising a rotating plate having camming surfaces of different elevation, a source of fluid pressure, a cylinder and piston, and a pawl actuated by said piston to move said plate step by step. 105 110 115

5. In a reamer cutting machine, the combination of a supporting base with a column, a cutter carried by said column, a table movably mounted on said column, a dividing head carried by said table, an eccentric shaft carried by said dividing head for rotatably supporting a reamer blank, means for feeding said blank against said cutter, means for rotating said blank step by step, means for raising said table to a predetermined elevation for each cut to vary the angularity and depth of teeth formed on said reamer, said means com- 120 125 130

prising a rotating plate having camming surfaces of different elevation, a source of fluid pressure, a cylinder and piston, a pawl actuated by said piston to move said plate step by step, and means actuated by a feeding movement of said table to control said piston.

6. In a cutting machine, the combination of a supporting base having a column with a table movably supported on said column and having a dividing head with a work supporting shaft, said shaft having an eccentrically located work holding arbor, a cutter carried by said column, means for moving said work holding arbor on said table into the path of said cutter to cut teeth converging toward a point eccentric with respect to the axis of the work, and means for rotating the work upon an eccentric axis into position for cutting other teeth, and means for raising and lowering said table a predetermined amount to regulate the depth of cut between the teeth of the work.

7. In a cutting machine, the combination of a supporting base having a column with a table movably supported on said column and having a dividing head with a work supporting shaft, said shaft having an eccentrically located work holding arbor, a cutter carried by said column, means for moving said work holding arbor on said table into the path of said cutter to cut teeth converging toward a point eccentric with respect to the axis of the work, and means for rotating the work upon an eccentric axis into position for cutting other teeth, and means for raising and lowering said table a predetermined amount to regulate the depth of cut between the teeth of the work, comprising a plate having a plurality of surfaces of predetermined elevation and means carried by said table for engaging said surfaces and raising or lowering said table on movement of said plate.

8. In a cutting machine, the combination of a supporting base having a column with a table movably supported on said column and having a dividing head with a work supporting shaft, said shaft having an eccentrically located work holding arbor, a cutter carried by said column, means for moving said work holding arbor on said table into the path of said cutter to cut teeth converging toward a point eccentric with respect to the axis of the work, means for rotating the work upon an eccentric axis into position for cutting other teeth, and means for raising and lowering said table a predetermined amount to regulate the depth of cut between the teeth of the work, comprising a plate having a plurality of surfaces of predetermined elevation and means carried by said table for engaging said surfaces and raising or lowering said table on movement of said plate, and means for automatically moving

said plate step by step to place the table at proper elevation before each cut.

In witness whereof, I hereunto subscribe my name this 30 day of November, 1929.

FRANS O. ALBERTSON.
